INKWELL FOR DESKS

John H. Oxley, Watertown, Mass.

Application December 14, 1937, Serial No. 179,684

11 Claims. (Cl. 120—67)

This invention relates to ink-wells which are primarily intended for use in school desks, in which the ink-well is located in an aperture formed in the desk top, but may be employed in any desk, or table in which an aperture or recess is provided to receive the ink-well.

Prior to my invention, the type of ink-well, which has been most generally used in recent years, has consisted of a glass receptacle having a flange at its upper end, which when installed, rests on an annular ledge extending about the aperture in the desk top in which the receptacle is located, the latter being provided with a closure which is attached thereto by screw threads and which is removed to fill or refill the receptacle.

In use considerable difficulty has been encountered from the fact that scholars frequently remove the ink-wells from the desks, spill the ink which they contain, and use them for missiles, so that much damage has frequently resulted.

Another difficulty has resulted from the fact that, as the ink-well depends into the desk it is liable to be upset by books, or other articles which are crowded into the desk, and which results in damage to its contents.

Also, ink-wells of this character have not usually been provided with a closure for the pen opening, or, if provided with a closure, they have usually been of the pivoted type which are adapted to be pushed aside, to permit access to the ink, and in most instances the user neglects to return it to closed position.

In consequence there is much loss of ink by evaporation and, when the ink dries in the well, it is often necessary to remove and wash it. Evaporation not only results in the loss of ink, but requires frequent attention on the part of the janitor, or other employee, to keep the ink-well filled.

The objects of my invention are to provide a form of ink-well which may be readily attached to any form of desk or table in such a manner that it cannot be removed by the application of ordinary pressure from beneath and from which the cover cannot be readily removed without the aid of a special tool or key for the purpose. Also to provide a form of closure for the pen opening in the cover, which may be readily pushed aside with the pen when it is inserted in the opening and which will automatically return to closed position immediately upon the withdrawal of the pen, so that the pen opening will always be tightly closed except when the pen is dipped into the ink.

I accomplish these objects by providing an outer casing, which is adapted to be permanently secured within the desk aperture, within which an ink receptacle is located, and to which a cover is attached in a manner to prevent ready removal unless a special tool or key is employed, said cover having its top side inclined downwardly to its pen opening thereby providing a raised rim portion which prevents overflow from accidental overfilling, and having a closure for the pen opening therein which consists of a metal ball, which is adapted to be readily pushed aside by the pen when inserted in the opening, but which immediately returns to closed position by gravity when the pen is withdrawn, said ball being attached to the cover by means of an arm which extends through the cover and has a knob on its inner end which prevents removal therefrom, said attaching means in no way interfering with the action in permitting the ball to be pushed aside by the pen when it is inserted and in automatic return thereof to closed position when the pen is withdrawn.

For a more complete disclosure of my invention, reference is now made to the following specification in connection with the accompanying drawing, in which:

Fig. 1 is a top plan view and Fig. 2 a side elevation of an ink-well embodying my invention.

Fig. 3 is a sectional view at line 3—3 of Fig. 1. 30

Fig. 4 is a sectional view at line 4—4 of Fig. 2.

Fig. 5 is a detail sectional view of the different parts.

Fig. 6 is a combined elevation and sectional view illustrating the action of the pen opening closure. 35

Fig. 7 is a sectional view illustrating the method of removing the cover.

Fig. 8 is a detail view of a key which is employed.

In the drawing *a* indicates a desk top having an aperture *b* extending therethrough, an inwardly projecting shoulder *c* being shown at the lower end of the aperture, although this is not essential, as the aperture may be of uniform diameter. 45

According to invention a cup shaped metal casing is provided having a semi-spherical bottom portion *10*, a cylindrical top portion *11*, and an intermediate circular transversely concave projecting rib *12*, the external diameter of said rib 50 being equal to the diameter of the aperture *b*, so that the casing fits snugly therein at this point.

To secure the casing in the desk aperture, lips *13* are struck out from said rib portion at several 55

points by means of a punch, or similar tool, so that, after the casing has been placed in position, it cannot be removed by force applied in either direction without breaking the wood. The internally concave formation of the rib portion permits the formation of the lips 13 to be readily performed, as the concave formation of the inner surface directs the tool to the points at which the lips should be formed. A similarly shaped ink receptacle 14 is also provided, which is formed to fit snugly in the casing and has an outturned flange 15 at its rim, which, when the receptacle is in position, rests on the rim of the casing. A cover 16 is provided, the top portion of which 15 is concave or is inclined downward from its rim to a central pen opening 17, said opening being circular and having a downturned lip extending about it. A cylindrical flange 18 depends from the rim of said cover which is adapted to fit 20 closely to the cylindrical upper portion of the casing, between the latter and the sides of the desk aperture. Inwardly projecting lugs 19 are indented in the flange 18 and correspondingly arranged outwardly projecting lugs 20 are indented in the cylindrical portion of the casing, 25 said lugs being helically formed, so that, when the cover is placed in position on the casing and turned clockwise, it will be screwed onto the casing and securely attached thereto. To permit ready removal and replacement of the cover, it is provided with two indentations 21 in its top 30 portion which are diametrically equidistant from the center of the cover, and a key 25 is provided, having two arms 26, which are adapted to be inserted in the indentations 21, and a middle arm 27, having a right angularly extending projection 28, which is adapted to be inserted in the pen opening 17. When the cover is to be removed the arm 27 is placed in the opening 17 in such a 35 position that its projection 28 engages the inner side of the cover and the arms 26 are placed in the indentations 21, and then the cover is turned slightly until the lugs 19 and 20 are disengaged. The cover is then lifted from the casing by the 40 key, as the arm 27 and its projection 28 acts as a hook to attach the cover thereto. The cover may be readily replaced by means of the key by a reverse operation, as will be obvious.

The closure of the pen opening consists of a 45 solid non-corrodible metal ball 22 having a rigid, curved arm 23 securely fixed therein, and said arm is extended through an aperture in the cover, in which it may move freely, and said arm has a knob 24 formed on the end thereof which is 50 adapted to engage the underside of the cover, so that the arm cannot be withdrawn from the hole, thereby securely attaching the ball to the cover and yet permitting free movement of the ball in 55 almost any direction, to permit a pen to be inserted in the pen opening.

As thus arranged, when a pen is to be dipped 60 in the ink contained in the receptacle, the pen is merely pressed between the ball and the cover, so that the ball is easily pushed aside, as shown 65 in Fig. 6, permitting the pen to be inserted in the receptacle, and when the pen is withdrawn, the ball immediately falls back into its former position by gravity, in which position it tightly 70 closes the pen opening. The arm 23 prevents insertion of the pen at the only point where insertion would not displace the ball, and it may 75 easily be displaced to permit insertion at any other point and will immediately fall back into closed position when the pen is withdrawn, so

that the pen aperture will always be tightly closed except when the pen is inserted therein.

The cover is so arranged that, when it is screwed onto the casing, it will be clamped against the flange 15 at the rim of the ink receptacle, so that the latter will be tightly closed at practically all times, and evaporation of ink will be effectively prevented. As the rim portion of the cover 16 is at a higher level than middle portion, when the receptacle is being filled by pouring ink through the pen aperture, if too much ink is poured in, the ink will overflow into the cavity formed by the cover and will not overflow onto the desk, as it will be retained by the raised rim of the cover. Also as the top surface 15 of the cover is concaved, so that it is inclined downward at all sides to the pen opening, the inclined surface aids in directing the ball to its seat in the opening. Also, the ball will not interfere with the insertion of the key 25, as before described, as the key will be inserted in a position in which its projection 28 will extend in the opposite direction from the arm 23 of the ball, as shown in Fig. 7.

The casing, cover and ink receptacle are all 25 formed from non-corrodible sheet metal, and may be formed by means of dies.

I claim:

1. In combination with an ink-well cover having a circular pen opening, and an aperture at 30 one side of said opening, a gravity actuated closure having a spherical face adapted to be seated in said opening, an arm fixed in said closure and extending through said aperture and freely movable therein, to permit displacement of said closure and return thereof to seated position, and means on said arm arranged to engage the cover to prevent withdrawal of the arm from said aperture.

2. In combination with an ink-well cover having a circular pen opening, and an aperture at 40 one side of said opening, a closure for said opening consisting of a spherical ball of greater diameter than said opening and adapted to be seated therein by gravity to close the same, an arm connected to said ball and extending through said aperture and freely movable therein, and means on said arm arranged to engage the inner side of the cover to prevent withdrawal of said arm from said aperture, said construction 50 permitting said ball to be pushed aside by the pen when inserted in said opening and to return to its seat by gravity.

3. In combination with an ink-well cover having a circular pen opening in the middle portion 55 thereof and an aperture at one side of said opening, a gravity actuated closure having a spherical face adapted to be seated in said opening to close the same, a curved arm fixed at one end in said closure and extending through said aperture and freely movable therein, and means on the inner end of said arm arranged to engage the inner side of said cover to prevent withdrawal of said arm from the aperture.

4. In combination with an ink-well cover having a circular pen opening in its middle portion and an aperture at one side of said opening, and having its top surface inclined downwardly from its rim to said opening, a gravity actuated closure having a spherical face adapted to be seated 70 in said opening to close the same, an arm fixed at one end in said closure and extending through said aperture and freely movable therein to permit said closure to be readily dislodged from its seat, and means on the inner end of said arm 75

arranged to engage the inner side of said cover to prevent withdrawal of said arm.

5. In combination with an ink-well cover having a circular pen opening in its middle portion and an aperture at one side of said opening, the top surface of said cover being inclined downwardly from its rim to said opening, a spherical metal ball greater in diameter than said opening and adapted to seat therein by gravity, a rigid arm fixed in said ball and extended freely through said aperture to permit ready displacement of said ball and means on the inner end of said arm adapted to engage the inner side of the cover to prevent withdrawal of said arm.

15. 6. An ink-well comprising a cup shaped casing having a cylindrical rim portion and adapted to be secured in a desk aperture, a cup shaped ink receptacle adapted to be seated within said casing, a cover having a pen opening in its middle portion, a liquid retaining edge portion raised above and enclosing said middle portion and a cylindrical flange depending from said edge portion and adapted to be fitted to said rim portion, and inter-engaging means on said flange and rim portion for attaching the cover to the casing.

20. 7. An ink-well comprising a cup shaped sheet metal casing having a cylindrical rim portion and an annular transversely concave rib projecting from the middle portion thereof, said rib being adapted to be fitted to a desk aperture and to be outwardly indented to secure the casing in the aperture, an ink receptacle adapted to be seated in said casing, and a cover having a pen opening and a depending flange at its edge adapted to be externally fitted to said rim portion within the aperture, said flange and rim portion having inter-engaging projections for securing the cover to the casing.

25. 8. An ink well comprising a sheet metal casing adapted to be secured in a desk aperture and having a cylindrical rim portion, an ink receptacle adapted to be seated within the casing, a cover having a central pin opening and diametrically disposed recesses at each side of said opening

and having a depending cylindrical flange at its edge adapted to be fitted to the rim portion of said casing, said flange and rim portion having oppositely extending projections adapted to be engaged and disengaged by turning the cover 5 with relation to the casing, and a key having arms adapted to be inserted in said recesses and having an intermediate arm adapted to be inserted in the pen opening, said intermediate arm having a projection at its end adapted to be engaged with the inner side of the cover.

10. 9. In combination with an ink-well cover having a circular pen opening, a gravity actuated closure having a spherically shaped face adapted to be seated in said opening, an arm connected 15 to said closure and extending therefrom, said arm having a freely movable connection with said cover permitting ready displacement of said closure, and automatic return thereof to seated position.

15. 10. In combination with an ink-well cover having a circular pen opening, a gravity actuated closure having a spherically shaped face adapted to be seated in said opening, an arm fixed in said closure and extending therefrom, said arm having a freely movable connection with said cover permitting ready displacement of said closure and automatic return thereof to seated position 20 and means on said arm to prevent disconnection of the closure and cover.

25. 11. In combination with an ink-well cover having a circular pen opening in its middle portion and having its top surface inclined downwardly to said opening, a gravity actuated closure having a spherically shaped face adapted to be seated 30 in said opening to close the same, an arm connected to said closure, having a freely movable connection with said cover, permitting ready displacement of the closure from its seat by the pen when inserted in said opening and return 35 thereof to seating position by gravity when the pen is withdrawn.

JOHN H. OXLEY.
